UNITED STATES PATENT OFFICE.

ISAAC E. SEXTON, OF WEST MEDFORD, MASSACHUSETTS.

SHEET-METAL CAN.

1,107,854.

Specification of Letters Patent.

Patented Aug. 18, 1914.

Application filed December 4, 1913. Serial No. 804,631.

To all whom it may concern:

Be it known that I, ISAAC E. SEXTON, a citizen of the United States, and a resident of West Medford, in the county of Middlesex and State of Massachusetts, have invented certain new and useful Improvements in Sheet-Metal Cans, of which the following is a specification.

This invention relates to sheet metal cans which are rectangular in cross section, the body of the can being composed of a blank bent to form four sides connected by curved corner bends, and the can being completed by uniting flanged heads to the ends of the body by continuous seams composed of the interlocked marginal portions of the head flange and the ends of the body, the seams being formed by a suitable seaming machine.

The object of the invention is to provide a rectangular can the body and heads of which are of such form that the above mentioned seams may be rapidly and economically made by a seaming machine, the seams being projected outwardly from the planes of the body sides, so that when several cans are stored or packed together they will contact with each other only at the seamed ends and their sides will be held apart without rubbing contact and defacement of labels, the formation of the body being such that the outward bulging of its sides by pressure of the contents of the can against them will be minimized and insufficient to cause contact between the sides of adjacent cans.

The invention consists in the improvements which I will now proceed to describe and claim.

Of the accompanying drawings: Figure 1 is an elevation of two cans (partly broken out) side by side to illustrate the space that exists between the flat sides of the bodies when the cans are either packed or set on a shelf; Fig. 2 is a top plan view of the adjacent corner portions of four cans constructed according to my invention; Fig. 3 represents a section on line 3—3 of Fig. 1, but illustrating four cans grouped as in Fig. 2. Fig. 4 is a fragmentary perspective view showing parts of two sides of the can body; Fig. 5 represents a section on line 5—5 of Fig. 4; Fig. 6 represents a section on line 6—6 of Fig. 4.

Similar reference characters indicate similar parts in all of the views.

The body of my improved can is composed of sheet metal bent to form four sides 10 con-

nected by curved corner bends extending from end to end of the body. The sides 10 are inclined outwardly at the ends of the body to form flaring portions 10^b between the corner bends. These flaring portions increase the area of the body at its ends and impart to the corner bend portions 10^c at the ends of the body, a relatively long radius enabling the seams which unite the heads to the body to be rapidly made by a seaming machine, as more fully explained hereinafter. In accordance with my invention the corner bend portions 10^a, connecting the major portions of the sides 10, are of much shorter radius than the bend portions 10^c, the radius of the bend portions 10^a being the shortest that will permit the bending of the metal without cracking. These short-radius bend portions are relatively stiff and inflexible so that they reduce the outward bulging of the body sides 10 to the minimum.

The heads 11 are alike in construction as to their marginal portions, which are united to the body, one of said heads being preferably provided with a neck 13. A description of one head will therefore suffice for both. The head has a flange 12, the base 12^b of which is formed to accurately fit the seat formed by the inner surface of the body portions 10^b and 10^c, said base having straight portions bearing on the flaring body portions 10^b, and curved corner bends 12^a bearing on the longer radius bend portions 10^c. In other words, the corner bends of the head flanges have a relatively long radius corresponding to that of the bend portions 10^c. The margin of the head flange 12 is adapted to be interlocked with the body end in the manner indicated by Fig. 1, or otherwise, by a seaming machine having a chuck engaged with the head and suitable mechanism adapted to bend the outer portion of the flange into interlocking engagement with the body. The relatively long radius of the flange bends 12^a and of the body bend portions 10^c enables the seaming machine to act rapidly in forming the curved portions as well as the straight portions of the seam, so that the time required for the seaming operation is reduced to the minimum, and the cost of manufacture is considerably less than it would be if the radius of the seam bends were the same as that of the body bend portions 10^c. It will be seen therefore that my invention insures stiffness at the corners of the body, preventing objectionable outward

bulging of the sides 10, and economy of time in seaming the heads to the body, these being important advantages. Another advantage is the protection of the sides 10 by the 5 projecting ends formed by the flaring body portions 10^b and the seams uniting the heads to the body. As shown by Figs. 1 and 3, said projecting ends space the sides 10 apart when several cans are stored or packed as 10 indicated, the spaces being so wide that the sides 10 of adjacent cans cannot possibly rub against each other and deface printed matter thereon.

Having described my invention, I claim:

15 A sheet metal can comprising a substantially rectangular body having sides connected by curved corner bends, the major portions of which are of relatively short radius, the major portions of the body-sides 20 being substantially flat and connected by the said short radius corner-bend portions, while the end portions of the body sides are flared outwardly between the corner bends, where-

by the radius of the end portions of the corner bends is increased, and heads having 25 marginal flanges seamed to the ends of the body, said flanges having straight portions connected by curved corner bends of relatively long radius conforming to the radius of the end portions of the body corner bends, 30 the outwardly flared portions of the body sides and the head flange portions engaged therewith forming projecting guards at opposite ends of the can, whereby contact between the flat side portions of adjacent cans 35 is prevented, the short radius of the major portions of the corner bends stiffening the corners of the body and minimizing the outward bulging of the flat side portions.

In testimony whereof I have affixed my 40 signature, in presence of two witnesses.

ISAAC E. SEXTON.
